US00D864959S

(12) **United States Design Patent** (10) Patent No.: **US D864,959 S**
(45) Date of Patent: **** Oct. 29, 2019**

(54) **COMPUTER GLASSES**(71) Applicant: **Mentor Acquisition One, LLC**,
Plantation, FL (US)(72) Inventors: **Ralph F. Osterhout**, San Francisco, CA
(US); **Mark Devin Kelley**, Oakland,
CA (US)(73) Assignee: **Mentor Acquisition One, LLC**,
Plantation, FL (US)(**) Term: **15 Years**(21) Appl. No.: **29/589,676**(22) Filed: **Jan. 4, 2017**(51) LOC (12) Cl. **14-02**

(52) U.S. Cl.

LLP(57) **CLAIM**

The ornamental design for computer glasses, as shown and described.

DESCRIPTION

FIG. 1 is a side view of an embodiment of the new design;
FIG. 2 is a bottom view thereof;
FIG. 3 is a front top perspective view thereof; and,
FIG. 4 is a rear bottom perspective view thereof.
The broken lines in FIGS. 1-4 are for environmental purposes only and form no part of the claimed design.
